Primary Examiner — Freda S Nunn(74) *Attorney, Agent, or Firm* — Lerner, David, Littenberg, Krumholz & Mentlik, LLP(57) **CLAIM**

The ornamental design for a notebook computer housing, as shown and described.

DESCRIPTION

FIG. 1 is a bottom front perspective view of a notebook computer housing shown in a closed configuration according to our design;

FIG. 2 is an enlarged portion of a section thereof as indicated in FIG. 1;

FIG. 3 is a top view thereof;

FIG. 4 is a bottom view thereof;

FIG. 5 is an enlarged portion of a section thereof as indicated in FIG. 4;

FIG. 6 is a front view thereof;

FIG. 7 is an enlarged portion of a section thereof as indicated in FIG. 6;

FIG. 8 is a back view thereof;

FIG. 9 is a right side view thereof;

FIG. 10 is a left side view thereof;

FIG. 11 is a top front perspective view thereof in an open configuration;

FIG. 12 is a top view thereof;

FIG. 13 is a bottom view thereof;

FIG. 14 is a front view thereof;

FIG. 15 is a back view thereof;

FIG. 16 is a right side view thereof; and,

FIG. 17 is a left side view thereof.

Broken lines are shown for environment only and form no part of the claimed design.
